UNITED STATES PATENT OFFICE.

JOSEPH N. TOMES, OF BUFFALO, NEW YORK, ASSIGNOR TO J. N. TOMES SMOKE CONSUMER AND FUEL ECONOMIZER CO., INC., OF BUFFALO, NEW YORK, A CORPORATION OF NEW YORK.

STEAM-BOILER FURNACE.

Application filed September 19, 1921. Serial No. 501,684.

To all whom it may concern:

Be it known that I, JOSEPH N. TOMES, a citizen of the United States, residing at Buffalo, in the county of Erie and State of New York, have invented certain new and useful Improvements in Steam-Boiler Furnaces; and I do hereby declare the following to be a full, clear, and exact description of the invention, such as will enable others skilled in the art to which it appertains to make and use the same.

This invention relates to a steam boiler furnace of smoke-consuming construction.

The main object is to improve the construction and render more efficient in operation the furnace disclosed in my application for Letters Patent of the United States Serial No. 324,866, filed September 19, 1919.

A particular aim is to provide a means whereby steam may be generated in less time than it requires in the apparatus of said pending application.

Another aim is to provide means whereby heated air from the firebox may be supplied by the fan employed to the boiler, and a vent means for combination with said means.

Additional objects and advantages will appear hereinafter from the description taken in connection with the accompanying drawings illustrating the practical embodiment.

In said drawings:—

Figure 1 is a front elevation of the improved furnace;

Figure 2 is a view thereof principally in longitudinal and vertical section; and

Figure 3 is a vertical sectional view on the line 3—3 of Figure 2.

Referring specifically to the drawings wherein like reference characters designate like or similar parts, a disclosure in the main is similar to that of the pending application referred to. A casing A is employed within which a boiler B is disposed above a grate C. The door to the firebox is shown at D while the door to the ash pit is illustrated at E. Grate C is supported by a fire wall F. Tubes G are disposed longitudinally of the boiler B at their front ends communicating with a smoke box H from which the stack extends at I. A damper J is provided in said stack I. A pipe or flue K communicates at one end with the stack I and at its other end with the ash pit.

A fan is provided at L, operable to induce air through a discharge pipe M, having a damper N therein, and which leads to a header O. The rear ends of the tubes G are open and the boiler is spaced from the rear wall to provide a chamber P. Branch pipes 2 extend through the rear wall of the casing A into the space P and terminate in line with and relatively close to the open rear ends of the tubes G.

The steam dome is indicated at B' and leading therefrom to a pipe R which communicates with the header O. Pipe R has a valve S therein.

In this instance, the air intake pipe for the fan L, which is shown at 4, extends upwardly, and is then elongated inwardly, being mounted in the rear wall of casing A and having its intake end disposed over or relatively close to the firebox so that heated air will be drawn in as the fan L operates. Operating with this intake, in order to supply proper draft, a pipe or stack 6 is secured in the casing A, in communication with the space P and to the atmosphere above the casing. This stack 6 is unobstructed throughout, as shown. Also in this instance swivel or other valves 7 and 8, are provided respectively, in the doors D and E, in order that they may be opened, when desired, to enable air to be drawn in therethrough.

In operation, with a fire on the grate C, fan L is operated, which will draw in air through the pipe 4—5 from the firebox, which will thus be heated, and discharge it through pipes M, header O, and pipes 2, into the pipe G and the flue K. During this operation of course the valve S is closed. As the heated air passes the gap between pipes G and 2, a vacuum is created, which draws the products of combustion into the pipe G and flue K. Due to the draft created in the furnace, products of combustion will bypass into the flue K and be discharged under the grate, so as to pass through the fire and thus become completely consumed. In the pending application referred to, the air drawn in and discharged through the pipe 2, is cold, which retards generation of steam. In this instance, the heated air is discharged in said pipe 2 and I find that steam can be generated in a much shorter period of time. The stack 6 provides the

necessary vent for effective operation of the pipe 5 in conveying heated air from the fire box.

When steam is generated, the valve N may be closed and valve S opened, so that steam will pass from the dome B' through the pipe R into the header O, and be discharged through pipes 2 into pipes G to effect a vacuum at the gap between pipes 2 and G for the same purpose as the heated air. Valves 7 and 8 may be adjusted when additional draft or air is desired.

My improvements have been found very effective in operation and to give a very considerable saving in the quantity of coal or other fuel which is used.

Changes in the spirit and scope may be resorted to.

What is claimed is:—

29 1. A furnace of the class described having a steam boiler, means for passage of air therethrough providing a gap within the furnace to induce products of combustion through the boiler, said means being in 35 communication with the firebox to convey heated air therefrom, and a vent means for the furnace to cooperate with said means and having its discharge end at said gap.

2. A furnace of the class described having a steam boiler, a casing with a wall spaced from the boiler to provide an outlet space for products of combustion, a stack leading from said space, a fan, an intake pipe for said fan extending through said

35 wall and having its intake end adjacent the firebox to receive heated air therefrom, a discharge means for said heated air leading from the fan having a plurality of tubes passing through said wall into said space and terminating short of the tubes of the 40 boiler to provide gaps, to induce products of combustion through the tubes of the boiler, and outlet flue means with which said boiler tubes communicate.

3. A furnace of the class described having 45 a steam boiler, a casing with a wall spaced from the boiler to provide an outlet space for products of combustion, a stack leading from said space, a fan, an intake pipe for said fan extending through said wall and 50 having its intake end adjacent the firebox to receive heated air therefrom, a discharge means for said heated air leading from the fan having a plurality of tubes passing 55 through said wall into said space and terminating short of the tubes of the boiler to provide gaps to induce products of combustion through the tubes of the boiler, outlet flue means with which said boiler tubes communicate, a flue leading from said outlet 60 flue means to the ashpit, and the ashpit and firebox doors having air inlet valves.

In testimony whereof I affix my signature in presence of two witnesses.

JOSEPH N. TOMES.
